UNITED STATES PATENT OFFICE.

ANDREW LARSON, OF OAKLAND, CALIFORNIA.

CUTTER-HEAD.

1,211,323.

Specification of Letters Patent. Patented Jan. 2, 1917.

Application filed December 13, 1915. Serial No. 66,611.

To all whom it may concern:

Be it known that I, ANDREW LARSON, a citizen of the United States, residing at Oakland, in the county of Alameda and State of California, have invented new and useful Improvements in Cutter-Heads, of which the following is a specification.

This invention relates to cutter heads especially designed for cutting lock joints and it consists in the novel features herein-after described and claimed.

An object of the invention is the provision of the cutter head of this character with which beveled joints, glue joints and the like may be accurately cut, the cutter head being readily adjusted to vary the size of the tongue, groove, and bevel which forms the cut.

Another object is the provision of a cutter head of this character which is simple in construction and reliable and efficient in operation, and which may be used on shaper, rip saw or sticker machines.

With the above objects in view the cutter head comprises a circular body adapted to be mounted in any suitable manner upon the shaft of a machine to which it is applied, the said body being provided at its periphery with arcuate recesses adapted to receive bits of various design or pattern, the said bits being used to cut the different surfaces of the joint as will be explained hereinafter. As some of the recesses are located opposite each other at the opposite sides of the body, while the other recesses are located at one side of the body only. The bits are secured in position in the recesses and at the side of the body by means of bolts which pass transversely through the bits and the body. These bolts are provided with key ways and keys are located in the body and enter the key ways and positively hold the bolts against turning movement.

Nuts are screwthreaded upon the bolts whereby the bits are securely held at adjusted positions with relation to the body.

With these objects in view the invention consists of the construction, combination, arrangement and design of cutter heads adapted to form lock joints, as will be more fully described hereinafter and illustrated in the accompanying drawing, and the novel features of which are particularly pointed out in the appended claim. It is to be understood however, that minor changes in details may be resorted to without depart-

ing from the spirit of the invention as set forth in the claim.

In the accompanying drawings:—Figure 1 is a top plan view of the cutter head. Fig. 2 is a similar view looking at the opposite side thereof. Fig. 3 is a transverse sectional view of the cutter head cut on the line 3—3 of Fig. 1. Fig. 4 is a similar view cut on the line 4—4 of Fig. 1. Fig. 5 is a similar view cut on the line 5—5 of Fig. 1. Fig. 6 is a fragmentary edge view of the head showing one arrangement of bits. Fig. 7 is a similar view showing another arrangement of bits. Fig. 8 is a similar view showing a bit in another form of recess. Fig. 9 is a similar view showing a bit positioned at the top of the head. Fig. 10 is a cross sectional view showing the form of joint which is cut by the cutter head.

The cutter head comprises a circular body 1, having a central opening 2 adapted to receive a shaft whereby the head may be positioned upon the rotating shaft of a machine in any suitable or usual manner. The body 1 is provided at its under side and at its periphery with arcuate recesses 3, the said recesses being disposed at diametrically opposite portions of the said body. Inasmuch as the recesses 3 are alike a description of one will answer. Each recess has converging side walls 4 and a bottom wall 5 which is disposed in a plane at an acute angle to the plane of the face of the body 1. Each recess 3 snugly receives a bit 6 and each said bit is provided with angularly disposed cutting edges 7 and 8. The cutting edges 8 are disposed substantially radially with relation to the body 1 while the cutting edges 7 are disposed at acute angles to the planes of the faces of the body 1. Both of the cutting edges 7 and 8 are disposed beyond the periphery of the body 1, as best shown in Fig. 2 of the drawing.

The body 1 is provided at its side opposite one of the recesses 3 with a recess 9 which is located at the periphery of the said body. The bottom wall 10 of the recess 9 is disposed at an acute angle to the bottom wall 5 of the opposite recess 3 and at an acute angle to the plane of the faces of the body 1. A bit 11 is located in the recess 9 and the said bit is provided with two angularly disposed cutting edges 12 and 13. The edge 12 is located at the inner side of the bit 11 and is disposed substantially radially with relation to the body 1, while the cut-

ting edge 13 is approximately parallel with the periphery of the body 1. A bolt 14 passes transversely through the bits 11 and 6 and is provided at the underside of its head with a chamfered surface 15 which bears against the outer side of the bit 11 at the center thereof and the said bolt is further provided along its shank with longitudinally disposed key ways 16. A key 17 is located in the body 1 and fits in the key way 16, the said key as shown in Fig. 3 of the drawing is disposed between the bits 6 and 11. A nut 18 is screwed upon the bolt 14 and bears at its inner face against the outer side of the bit 6 at the center thereof and serves as means for securely holding the bits 6 and 11 at adjusted positions in the recesses 3 and 9 respectively.

The body 1 is provided at the same side 20 at which the recess 9 is located with another recess 19 which is also located at the periphery of the body 1. The recess 19 is arcuate in plan and is opposite the other recess 3. The bottom wall 20 of the recess 19 is disposed at an acute angle to the plane of the faces of the body 1 but lies parallel with the bottom wall 5 of the recess 3 directly opposite the said recess 19. A bit 21 is fitted in the recess 19 and the said bit 21 is 25 provided with two angularly disposed cutting edges 22 and 23, the cutting edge 22 is located at the outer side of the disk 21 and is disposed approximately radially with relation to the body 1 while the cutting edge 30 23 is disposed approximately parallel with the periphery of the body 1. It will be observed that the bits 11 and 21 are of the same general pattern, the exception being that the radially cutting edge 12 of the bit 35 11 is located at the inner side of the bit while the radial cutting edge 22 of the bit 21 is located at the outer side of the said bit 21. The cutting edges 13 and 23 of the bits 11 and 21 lie substantially in the same 40 path of travel in a direction parallel with the plane of the face of the body 1.

A bolt 24 passes transversely through the bit 21 and the opposite bit 6 and the edge portion of the body 1 and the head of the bolt 24 bears against the outer side of the bit 21 while a nut 25 is screwthreaded upon the bolt 24 and bears against the outer surface of the opposite bit 6. The bolt 24 is provided with a key way 26 which receives 45 a key 27 located in the body 1 between the bits 21 and 6. Therefore it will be seen that when the nut 25 is tightened, the bolt 24 is positively held against turning movement in the body 1, and the bits 21 and 6 are securely held at adjusted position in the respective recesses which receive the same.

The body 1 is provided at the same side at which the recesses 9 and 19 are located with other recesses 28. The recesses 28 are 50 located at the periphery of the body 1 and

are at diametrical opposite points thereof. Bits 29 are located in the recesses 28 and are held therein by means of bolts similar to the bolt 24 hereinbefore described. The bits 29 are provided with concaved peripheries which terminate at one end in concaved cutting edges 30 disposed transversely with relation to the body 1 but located beyond the periphery thereof.

Bits 31 are positioned upon the body 1 at the same side thereof at which the recesses 28 are located and the bits 31 are held in position upon the body 1 by means of bolts and their attachments similar to those in connection with the bolt 14 hereinbefore described. The bits 31 are provided at their outer sides with conical surfaces 32 which terminate at one end in cutting edges 33 disposed approximately radially with relation to the body 1 and at an acute angle to the faces thereof.

The cutter head as shown and described when applied to a rotating shaft may cut at the edge of a strip of wood a joint consisting of inner and outer bevel surfaces a tongue located adjacent one bevel surface and a groove between the tongue and the inner edge of the other beveled surface as shown in the accompanying drawing. Furthermore the edges of the tongue are chamfered which is accomplished by the concaved cutting edges 30 of the bits 29. The cutting edges of the bits 6 cut one beveled surface on the stick of timber, the cutting edges 33 on the bits 31 cut the other beveled surface on the said stick of timber and the cutting edges 12 and 13 of the bit 11 and 22 and 23 of the bit 21 form the bottom and opposite side walls of the groove which is adjacent the tongue on the stick of timber. It is apparent that by providing such joints at the edges of two sticks of timber by passing the timber by the cutter head in planes at angles to each other the said joints will interfit and interlock and by providing the beveled edges at the tongues sufficient space is left for the reception of glue or other adhesive whereby the said sticks of timber may be securely glued and held together.

It is also apparent that by adjusting the two bits 11 and 21 circularly in their respective recesses 9 and 19, the depth of the groove which is cut in the timber may be regulated and also the transverse thickness of the tongue of the stick of timber may be increased or diminished. When it is desired to provide a joint with only one beveled surface the bits 31 may be turned so that their cutting edges 32 are brought with the periphery of the body 1.

From the foregoing description taken in conjunction with the accompanying drawings it will be seen that a cutter head of simple and durable structure is provided

and that the same may be efficiently used for accurately cutting lock joints to be used for joining strips or sticks of wood together.

Having described the invention what is 5 claimed is:—

A cutter head comprising a body having recesses, a bit mounted in a recess at one side thereof and adapted to cut a beveled surface upon a stick of timber, another bit 10 mounted in a recess at the opposite side thereof and adapted to cut a groove in the stick of timber, said groove being spaced from said bevel surface thereby leaving a tongue between the groove and the bevel 15 surface, another bit mounted in a recess of

the body and lying between the sides thereof and adapted to chamfer the edges of the tongue which is left between the groove and the said bevel surface and a fourth bit mounted upon the body and disposed beyond the side thereof and adapted to cut a bevel surface upon the stick of timber adjacent the said groove. 20

In testimony whereof I affix my signature in presence of two witnesses.

ANDREW LARSON.
